CYLINDER COVER STRUCTURE

Charles W. Dake, Grand Haven, Mich.

Application November 15, 1937, Serial No. 174,589

3 Claims. (Cl. 123—173)

My present invention relates to cylinder covers and particularly to an improved cylinder cover structure adapted to be applied to cylinder blocks of internal combustion engines for closing the 5 end of the piston excursion bore thereof and to provide a combustion chamber pocket for such engines; and the objects of improvements are, first, to provide a cylinder cover of such structure that will permit an extremely high rate of fuel 10 charge compression and resultant combustion pressure to be utilized; second, to provide a cylinder cover structure in which the high temperature produced by combustion of a highly compressed charge of gaseous fuel within the combustion spaces of the engine will be transferred to the cooling medium of the engine with a minimum of resistance; third, to provide a cylinder structure that can be readily adaptable to internal combustion engines of widely different 15 designs and construction; and, fourth, to provide a cylinder cover structure having the above named objects that will be simple, cheap to manufacture and readily understood.

I attain the above named objects as well as 20 other objects that will be apparent from a perusal of the herewith description when taken in connection with the accompanying drawings, of which:

Figure 1 is an under plan view of a portion 25 of the combined leak sealing gasket, combustion chamber forming and heat transfer member of my cylinder cover structure.

Figure 2 is an under plan view of a portion of 30 my cast metal body of said cylinder cover structure with the gasket removed.

Fig. 3 is a vertical cross-sectional view taken 35 through Fig. 1 of the assembly of the cylinder cover and sealing gasket.

Figure 4 is a cross sectional view of the 40 combined pressure sealing gasket, combustion chamber forming and heat transfer member as taken on line X—X of Fig. 1, when removed from the cover body.

Figure 5 is a cross-sectional view of my cylinder 45 cover structure taken on line I—I of Figure 2.

Referring to the several views of the drawings, similar numerals refer to similar parts as follows:

50 Numeral 1 designates a fragmentary portion of the cast ferrous metal body member of my improved cylinder cover structure having therein cooling fluid chamber 2 with opening 3 extending therefrom to the machined face 4 thereof and 55 conforming substantially to the outer form of the

combustion chamber wall, spark plug depression 5, boss 6 extending into the cooling fluid chamber below said spark plug depression and having axially thereof bore 7, drilled holes 8 through which studs or screws for securing the cover structure to the cylinder block of the engine extend and cooling fluid circulating holes 9. Numeral 10 designates the combined pressure sealing gasket, combustion chamber forming and heat transfer member formed preferably from 10 copper plate and has depressed therein combustion chamber 11 comprising a dome-like portion 13 and extending into the said opening 3, with a portion extending into the bore 7 of the boss 6; internally screw-threaded bushing 14 and inclined sloping portion 15 over the piston excursion bore 16 of the engine's cylinder block 17 which has therein cooling fluid chambers 18; fuel inlet port 19 with inlet valve 20 closing the top thereof during the time period the piston is on 20 its compression and working excursions. Numeral 21 designates pressure sealing fins, ribs or ridges at each flat side of the combined pressure sealing gasket, combustion chamber forming and heat transfer member, which fins or ridges 25 extend annularly around the stud or screw holes 22, cooling fluid holes 23 and around the combustion chamber 11 in close proximity to the border edge thereof and also to the edge of the opening 3, and by their deformation, when the 30 cover structure is applied to the cylinder block and drawn thereagainst by the holding studs or screws, are deformed and thereby compelled to conform to any irregularities of the top surface of the cylinder block and the machined face 35 around opening 3 of the cast metal body member of the cylinder cover structure.

In producing my present cylinder cover structure, to produce the body portion 1 thereof, I cast 40 the said body portion by the usual foundry method of casting hollow members. Having produced the said body casting, I machine the casting at one of its broader sides to provide the machined surface 4, drill and ream the several stud or screw holes 8 and bore 7 and counter ream around the bore 7 within the spark plug depression 5. In producing the combined pressure leak sealing gasket, combustion chamber forming the heat transfer member, I utilize a metal plate of uniform and desired thickness, preferably of soft copper, from which I cut a blank corresponding to the outer edge shape required and place the said blank between dies in a suitable press by the operation of which the several holes there- 55

through are punched and the combustion chamber drawn or pressed therein and thereafter undercut or roll the pressure sealing fins or ridges in both sides of the formed combined pressure sealing gasket, combustion chamber forming and heat transfer member.

Having produced the above named members of my cylinder cover structure substantially as described and desiring to apply it to a cylinder 10 block, I first apply the combined pressure sealing gasket, combustion chamber forming and heat transfer member against the cylinder block over the piston excursion bore thereof with the open side of the combustion chamber facing 15 the said cylinder block, then place against said member 10 the cylinder cover body 1 in such manner that the internally threaded bushing 14 is situated in the bore 7 of the boss 6 and then 20 secure the said structure to the cylinder block as by suitable studs or screws and thereafter apply the spark plug by screwing it into the internally threaded bushing 14 and draw the said bushing tightly into the bore 7 with the top 25 wall of the combustion chamber resting against the boss 6.

In my improved cylinder cover structure, I obtain a maximum transfer of heat generated by combustion of the fuel in the combustion spaces of the engine, as the copper, from which the combustion chamber is preferably made, having a very low resistance to the flow of heat through it and being directly in contact with the cooling fluid within the cooling fluid chamber offers only slight resistance to the transfer of heat to said 35 cooling fluid. Therefore, a much higher rate of compression and consequent high temperature of combustion can be employed, which results in a

minimum of fuel consumption by the engine without undue ignition detonation therein and permits a low grade of fuel to be utilized.

Having described my present invention, the rights which I desire to secure are set forth in 5 the following claims, as follows:

1. A cylinder cover structure comprising a cast ferrous metal body having a plane face, and a cooling fluid chamber therein and having an opening extending to said face and a combined 10 pressure sealing gasket, combustion chamber forming and heat transfer member of non-ferrous metal located against the said face of the said metal body and having a combustion chamber formed therein with the walls thereof extending through said opening into the said cooling fluid chamber.

2. A cylinder cover structure comprising a cast ferrous metal body having a plane face, a cooling fluid chamber having an opening extending 20 to said face, a combined pressure sealing gasket, combustion chamber and heat transfer member of non-ferrous metal located against the face of the said cast metal body and having a combustion chamber formed therein.

3. In a cylinder cover structure, the combination comprising a cast ferrous metal body having integral side, top, and bottom walls, with a cooling fluid chamber therebetween, the said bottom wall having an opening extending there- 30 through with a combined pressure sealing gasket, heat transfer and combustion chamber forming member of non-ferrous metal extending through said opening into the said cooling fluid chamber and against the said face of the cast ferrous 35 metal body.

CHARLES W. DAKE.
